[57] **CLAIM**

The ornamental design for an ultrasonic object detection device, as shown.

DESCRIPTION

FIG. 1 is a perspective view of an ultrasonic object detection device showing my new design.

FIG. 2 is a rear elevational view thereof.

FIG. 3 is a front elevational view thereof.

FIG. 4 is a right side elevational view thereof.

FIG. 5 is a left side elevational view thereof.

FIG. 6 is a top plan view thereof.

FIG. 7 is a bottom plan view thereof.

The termination of the wires shown extending from the front indicate wires of an indeterminate length.
